UNITED STATES PATENT OFFICE.

BURTON B. ANNIS, OF COLUMBUS, OHIO.

GAS GENERATOR.

Application filed July 18, 1925. Serial No. 44,553.

This invention relates to gas generators, and has for an object the provision of a container for fluid and a submerged container for material such as iron sulfid in such relation to the first mentioned container that the fluid in the first mentioned container may have access to the second mentioned container proportional to the requirements and proportional to the pressure of gas developed through the moistening of the iron sulfid, (to be hereinafter referred to as the "charge"), as fluid gains access to the said charge.

It is an object of this invention to produce a gas generator in which novel means are provided for maintaining the apparatus against fouling which might be due to the accumulation of spent charges at the bottom of the apparatus.

It is furthermore an object of this invention to provide novel means for preventing the development of excessive pressure within the apparatus.

It is a further object of the invention to provide means for so regulating the pressure as to prevent injury to parts of the apparatus or to objects exterior of the apparatus, through the employment of an equalizer by which the generation of gas is controlled.

It is a still further object of this invention to produce a generator of the character indicated, the parts of which can be readily assembled or dismantled and in which the charge can be expeditiously renewed.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a sectional view of a generator embodying the invention;

Figure 2 illustrates a sectional view of the device on the line 2—2 of Fig. 1 with the charge omitted; and

Figure 3 illustrates a sectional view on the line 3—3 of Fig. 1.

In these drawings, 5 denotes a tank or container which is rather high and narrow, the said container having a lid 6 and a drain cock 7, the latter being located at the bottom

of the container and effective to permit the withdrawal of the spent acid or sludge in order that the device may be freed of such acids and the container may be maintained in a highly efficient state of operation.

The pipe 8 is located vertically in the container and extends exteriorly thereof at the top where it is provided with any suitable service pipe 9 that may lead to a source of consumption. The pipe 8 has a gooseneck or loop 10 at the bottom of the container and the inner end of the pipe is located a suitable distance above the bottom of the container.

A charge receiving jar or holder 11 when in operative relation to the container is bell-shaped and preferably it has a handle 12 at its top to facilitate its application to and removal from the container. On the interior of the wall of the said holder 11 there is a curved partition or wall 13 integral with or so connected to the holder as to produce a tight joint. The curved partition with the wall of the holder forms a chamber in which the upward extension of the pipe 8 is located, and the said pipe terminates below the upper end of the said partition.

The partition has a port or opening 14 at its upper end which permits gas to pass from the holder to the said chamber and to and into the pipe where under pressure it is forced to the service pipe 9.

The interior wall of the bell or holder is further provided with segmental flanges 15 and 16 that extend inwardly and form supports or shelves for the bottom 17 of the holder, which bottom is perforated to permit fluid to pass into the holder in order that it will gain access to the charge 18 within the holder, and the said apertures further permit the escape of spent acid or sludge which may gravitate to the bottom and be discharged, as heretofore indicated. The bottom 17 is so shaped that it will clear the edges of the flanges 15 and 16 when inserted, and when turned, will be supported by the said flanges.

The holder is supported in the container clear of the bottom thereof by a suitable base 19 of appropriate construction, and the inventor does not wish to be limited with respect to the particular form of the base.

In carrying the invention into practice, the holder is filled with a charge of solid material such as FeS, CaCO₃ or the like and the bottom or plate 17 is inserted and held

in place by the interengaging parts heretofore described, and the said holder is then placed in the container. The fluid which is in the nature of an acid is then added to the container and if the pipe 8 is opened, gas which is generated in the holder is forced out by the pressure of the column of liquid in the container. As the pressure in the holder is reduced, acid is permitted to rise through the plate 17 and when the charge is submerged, gas is instantaneously generated. The greater the discharge of gas through the pipe, the greater the height of the acid will be in the holder, and therefore, the gas will be generated more speedily up to the capacity of the generator.

If the passage of gas through the pipe 8 is interrupted, the gas being generated is unable to escape from the jar and its pressure forces the acid out of the holder through the plate or bottom 17. The acid which coats the charge, and which remains after the acid has been forced out of the holder is quickly spent; and a small reserve chamber is provided below the plate as a storage for the gas generated by the residual acid, it being shown that the plate 17 is located a distance above the lower edge of the holder.

In case the generator is subjected to a gas pressure beyond its capacity, as when a connection is accidentally broken, the acid rises in the holder until the outlet pipe is submerged and the line at once fills to the level of the acid in the container but not higher, as the system is then in equilibrium. The arrangement of parts, therefore, automatically controls the operation of the generator and interrupts the development of gas or pressure, and the apparatus can only be restored to operative condition by blowing the pipe clear of fluid to permit gas to again flow. The provision for interrupting the functioning of the gas generator is of importance when the device is used for the production of poisonous gases as a room or compartment cannot be accidentally flooded with the gas.

It will be seen from an inspection of the drawing and from the foregoing description that the apparatus is a compact structure and that the pressure can be regulated by varying the height of the liquid in the container. The capacity of the holder is such and the arrangement for filling the said holder as

provided permits the use of relatively large pieces of solid material in the holder, and the said holder can be filled and emptied expeditiously. The device is constructed without connections that are liable to become weak and produce leaks and the construction is such that there are no restricted passages to become fouled or choked.

I claim:

1. In a gas generator, a liquid container, a bell-shaped charge holder therein, means for supporting the charge holder above the bottom of the container, a perforated bottom for the charge holder, means for holding the bottom in the charge holder above the lower edge of the charge holder, a vertical partition in the holder, the said partition having a port in its upper end communicating with the charge area of the holder, a pipe standing in the container and having a discharge end located above the liquid in the container, the said pipe having a gooseneck portion extending upwardly into the space between the inner wall of the holder and the said partition whereby gas generated in the holder escapes through the said pipe.

2. In a gas generator, a liquid container, a bell-shaped charge holder therein, segmental flanges extending inwardly from the inner wall of the holder, a bottom fitted to the interior of the holder and supported on the flanges, the said bottom being arranged to permit fluid to enter the holder from the container, a vertical partition in the holder, the said partition having a port in its upper end communicating with the charge area of the holder, a pipe standing in the container and having a discharge end located above the liquid in the container, the said pipe having a gooseneck portion extending upwardly into the space between the inner wall of the holder and the said partition whereby gas generated in the holder escapes through the said pipe.

3. In a gas generator, a liquid container, a bell-shaped charge holder supported therein near the bottom, means for supporting a charge in the charge holder, a pipe extending vertically in the liquid container and having a gooseneck portion projecting upwardly into the charge holder for receiving gas from a location near the top of the charge holder.

BURTON B. ANNIS.
